UNITED STATES PATENT OFFICE.

ALFRED L. SOHM, OF CHICAGO, ILLINOIS.

LOCKING DEVICE FOR RADIATOR CAPS.

Application filed September 21, 1925. Serial No. 57,731.

This invention relates to locking devices for radiator caps and more particularly to a device adapted to support a radiator signal ornament or the like and provided with manually controlled means for locking it securely to a radiator spout to prevent its unauthorized removal.

In a copending application Serial No. 31,153, filed May 18th, 1925, I have shown a radiator cap provided with a central bearing carrying a rotatable screw having a fixed ratchet secured thereto and adapted to be engaged by a spring pressed pawl to prevent reverse movement of the screw. Beneath the bearing an internally threaded collar surrounds the screw and supports the lower ends of outwardly and upwardly extending arms which are pivotally connected to the collar. The arms are adapted to contact with the lower end of the bearing whereby the outer ends thereof will be moved outwardly into engagement with the interior of the radiator spout when the screw is revolved to elevate the collar.

The present invention is an improvement over the construction shown in my copending application above identified and has for an object the provision of means for preventing reverse rotation of the locking screw by means of a gravity operated pawl whereby the cap may be removed without damage to itself or the radiator spout, if removal is necessary, by detaching the radiator and inverting it whereby the pawl will move away from the ratchet to permit reverse rotation of the screw.

A further object is to provide a cap which is not in threaded engagement with the radiator spout whereby a cap of one size may be made to accommodate radiator spouts of varying sizes.

A still further object is to provide a cap formed in two pieces, the inner piece carrying the locking means whereby it will be securely locked to the radiator spout against any movement, the outer piece being held in position by the inner piece to prevent its removal, but being freely rotatable whereby an attempt to remove the device by an unauthorized person will prevent any injury to the locking mechanism.

Other objects and advantages of the invention will become apparent during the course of the following description.

In the drawings I have shown one embodiment of the invention. In this showing:

Figure 1 is a central vertical sectional view through the device in position on a radiator spout, parts being shown in elevation,

Figure 2 is a plan view of the lock supporting member,

Figure 3 is a perspective view of the collar and locking arms,

Figure 4 is an underside perspective of the lock supporting member, and,

Figure 5 is a similar view of the locking screw.

Referring to the drawings, the numeral 10 designates the spout of an ordinary automobile radiator. The device forming the subject matter of the present invention comprises an outer collar 11 which may be provided on opposite sides with ornamental arms 12. The collar 11 is provided in its under side with a cylindrical opening 13 preferably somewhat larger than the average size radiator spout and adapted to receive spouts of somewhat varying sizes. The collar 11 is provided with an upper horizontal portion 14 having a groove 15 in its upper face for the reception of a rubber or similar gasket 16 for a purpose to be described. The upper portion of the collar 13 is further provided with a horizontal shoulder 17.

The numeral 18 designates a lock supporting member as a whole comprising an upper horizontal ring 19 having an annular flange 20 extending outwardly to engage the upper face of the shoulder 17, as shown in Figure 1. A gasket 21 is arranged between the collar 11 and the upper end of the radiator spout to prevent leakage of water or water vapor when the device is in position and in normal operation. The lock supporting member further includes a plurality of depending fingers 22 each of which is provided in its outer face with an upwardly extending groove 23 forming arms 23'. A ring 24 is preferably formed integral with the fingers 22 at their lower ends and an integral cylindrical member or thimble 25 depends from the ring 24, as shown in Figures 1 and 4. The arms 23' extend downwardly a short distance below the ring 24 to form guides in a manner to be described.

The thimble 25 is provided with a cylindrical bore 26 for a purpose to be described and the thimble is provided with a closed lower end 27, the inner face of which is provided with circularly arranged ratchet teeth 28.

The numeral 29 designates a collar adapted to slide upon the thimble 27, as shown in Figure 1. The collar 29, as shown, is provided with a cylindrical bore in which the thimble is adapted to slide. The collar 29 is provided at spaced intervals with notches 31 in its upper edge in which are arranged the lower and inner ends of arms 32, as shown in Figure 3. Pins 34 extend through the notches 31 and arms 32 whereby the latter are pivotally connected to the collar, as will be understood. The outer ends of the arms 32 are provided with relatively sharp edges 35 which are adapted to grip against the inner surface of the radiator spout in a manner to be described. The arms 32 correspond in arrangement to the grooves 23 and are adapted to operate therein.

The thimble 25 and collar 29 are provided with aligned axial openings 36 and 37 respectively to receive the shank of a screw 38, as shown in Figure 1. The screw is provided at its upper end within the bore 26 with an enlarged head 39 having a screw driver slot 40 formed in its upper face. The head 39 is undercut as at 41 to form a recess having a vertical wall 42. A pawl 43 is pivotally connected as at 44 to the head 39 against the vertical face 42, as clearly shown in Figure 5. When the device is assembled as shown in Figure 1, the bore 26 is preferably closed by a lead or similar soft metallic slug 40' in the form of a disk snugly fitting within the bore against the upper face of the head 39.

A ring 45 is arranged above the collar 11 and lock supporting member 18, as shown in Figure 1 and this ring is provided on its lower face with an annular rib 46 adapted to be clamped in any suitable manner against the gasket 16. The ring 45 is preferably pivotally connected to the collar 11 by any suitable form of hinge (not shown) such as is shown in my copending application above identified. The ring 45 is further provided centrally thereof with an opening 47 to permit the passage of water vapor therethrough. In the present showing of the device I have illustrated a radiator signal including a cylinder 48 having its lower end arranged in an annular recess 49 formed in the upper face of the ring 45. In my copending application Serial No. 4,589, filed January 24th, 1925, I have shown and described a radiator signal having a cylinder similar to that previously described and adapted for arrangement within the recess 49. The signal referred to includes a movable cap 50 adapted to be actuated by fluid pressure generated by the

boiling of the water in the radiator to warn the driver of the vehicle when unusual conditions exist in the radiator. It will be obvious, however, that any suitable form of signal or ornament may be supported by the locking cap.

An operation of the device is as follows:

As previously stated, the opening 13 of the collar 11 is preferably sufficiently large in diameter to accommodate radiator spouts of varying sizes and it is unnecessary for the spouts to contact with the interior of the collar as will become apparent. When the device is to be applied to the radiator, the collar 29 is arranged near the lower end of the screw 38 whereby the arms 32 may be swung inwardly a material distance beyond the position shown in Figure 1. The device is then placed in position over the radiator and the ring 45 opened to permit access to the locking mechanism. With the device pressed downwardly with the gasket 21 firmly engaging the upper end of the radiator spout and the device approximately centered over the spout, a screw driver may be employed for rotating the screw 38 in a clockwise direction when looking down on the device. Rotation of the screw obviously will elevate the collar 29 and contact between the lower ends of the fingers 22 and the arms 32 will cause the latter to swing outwardly. Continued rotation will move the arms 32 outwardly until the edges 35 at the outer ends of the arms firmly grip against the inner face of the radiator spout. The pawl 43 is normally in contact with the ratchet teeth 28 and when the arms 32 assume a locking position, disengagement thereof is prevented since the pawl 43 will prevent reverse rotation of the screw. The contact between the pins 34 and arms 32 is preferably sufficiently snug to normally maintain the free ends of the arms at their inner positions until they are moved outwardly by elevation of the collar 29. If the arms 32 are loosely pivoted, a small rubber band or piece of cord may be wrapped about the arms to prevent them from falling prematurely and becoming disengaged from between the lower ends of the guide arms 23. It will be obvious that the arrangement of the arms 32 between the arms 23 will prevent rotation of the collar 29 while the screw is being operated. If desired, a lead or similar slug 40' in the form of a disk may be driven downwardly within the bore 26 against the upper face of the screw head 39 after the device has been installed on a radiator. This slug serves to cover the screw and the slot 40 in the head thereof and its inclusion in the device is intended to discourage attempted theft of the device since it would be necessary to spend some little time removing the slug before the screw head would be accessible. The slug itself is

not intended to be a positive protection to the device since the screw cannot be rotated to permit release of the arms 32.

It will be apparent that the locking device just described will prevent removal of the cap and the radiator signal or other device carried thereby, by unauthorized persons. If it ever becomes necessary to remove the locking cap, this can be done by removing the radiator from the vehicle and inverting it, whereupon the screw may be rotated slightly to free the pawl 43 and the screw then can be backed out to permit the arms 32 to be withdrawn.

It will be apparent that the clamping action will firmly engage the flange 20 against the shoulder 17 and maintain the ornamental arms 12 in their proper position transversely of the vehicle. If any unauthorized person attempts to twist the device loose by rotating the arms 12, the collar 11 may be rotated against the frictional engagement just described and the locking mechanism will not be disturbed and thus will be protected from injury.

It is to be understood that the form of my invention herewith shown and described is to be taken as a preferred example of the same and that various changes in the shape, size and arrangement of parts may be resorted to without departing from the spirit of the invention or the scope of the subjoined claims.

I claim:

1. A device of the character described comprising a cap adapted to be arranged over the filling spout of an automobile radiator, a plurality of depending members carried by said cap and provided with guides, a screw supported by said depending members and rotatable in one direction, means for preventing reverse rotation of said screw, a collar threaded on said screw, and a plurality of upwardly diverging arms pivotally connected at their lower ends to said collar and slidable in said guides.

2. A device of the character described comprising a cap adapted to be arranged over the filling spout of an automobile radiator, a plurality of depending members carried by said cap and provided with guides, a thimble carried by the lower ends of said depending members and provided with an axial opening, a screw arranged in said opening and rotatable in one direction therein, means for preventing reverse rotation of said screw, a collar threaded on the lower end of said screw and slidable on said collar, and a plurality of upwardly diverging arms pivotally connected at their lower ends to said collar and slidable in said guides.

3. A device of the character described com-

prising a cap adapted to be arranged over the filling spout of an automobile radiator, a plurality of depending members formed integral with and depending from said cap, said members being provided on their outer faces with guides, a thimble formed integral with said members and provided in its upper end with a bore, said thimble being provided in its lower end with a relatively small opening, the upper face of the bottom of said thimble being provided in its lower end with a relatively small opening, the upper face of the bottom of said thimble being provided with ratchet teeth surrounding said opening, a screw arranged in said opening and provided with a head arranged in said bore, a gravity operated pawl carried by the head of said screw and adapted to engage said ratchet teeth, a collar threaded on said screw below said thimble, and a plurality of upwardly diverging arms pivotally connected at their lower ends to said collar and slidable in said guides.

4. A device of the character described comprising a cap adapted to be arranged over the filling spout of an automobile radiator, a thimble formed integral with said cap and depending therefrom, said thimble being provided in its lower end with a central opening and in its upper end with an enlarged bore communicating with said opening, a screw arranged in said opening and provided with a head arranged in said bore, a collar threaded on said screw below said thimble, a plurality of upwardly diverging arms pivotally connected at their lower ends to said collar, said arms contacting with a portion of said cap to move the upper ends thereof outwardly as said screw is rotated in one direction, means for preventing reverse rotation of said screw, and a cap frictionally held within the bore of said thimble above the head of the screw therein.

5. A device of the character described comprising a pair of members forming a cap adapted to be arranged over the filling spout of an automobile radiator, one of said members having portions depending within the radiator spout and provided with guides, the other of said members being fixed against removal from said first named member but rotatable with relation thereto, a rotatable screw carried by the depending portion of said first named member, a plurality of locking arms each having a portion arranged in one of said guides, the inner ends of said locking arms projecting inwardly beyond said guides, and means for moving the inner ends of said locking arms vertically upon rotation of said screw.

In testimony whereof I affix my signature.

ALFRED L. SOHM.
